Primary Examiner — Marie D. Fast Horse(74) *Attorney, Agent, or Firm* — Sughrue Mion, PLLC(57) **CLAIM**

The ornamental design for a SSD storage device, as shown and described.

DESCRIPTION

FIG. 1 is a perspective view of SSD storage device showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a cross-sectional view taken along line VIII-VIII of FIG. 2; and,

FIG. 9 is a cross-sectional view taken along line IX-IX of FIG. 4.

The broken lines in the drawings depict a portions of the SSD storage device that form no part of the claimed design.

1 Claim, 5 Drawing Sheets(56)
